L. UNGER

METAL SAFETY SEAL FOR ENVELOPES AND THE LIKE

Filed April 5, 1926

LOUIS UNGER,
Inventor

By his Attorney Julian J. Wittal

UNITED STATES PATENT OFFICE.

LOUIS UNGER, OF ELYRIA, OHIO.

METAL SAFETY SEAL FOR ENVELOPES AND THE LIKE.

Application filed April 5, 1926. Serial No. 99,762.

This invention relates to safety seals for use in connection with envelopes, express packages and other carriers of valuable papers or documents and has for its main object to provide a metal structure of the above described character whereby letters and other matter enclosed in envelopes cannot be removed by unauthorized persons without detection.

A feature of the invention resides in the provision of a male member or base plate having integrally tapered prongs struck up therefrom, and a female or cap member provided with pockets to receive and clinch said prongs to lock the parts in fixed relation so that it would be necessary to tear the flap of the envelope, or the paper wrapper of an express package, to get at the contents thereof. The clinching pockets are preferably shaped so that the clinched or turned back terminals of the prongs lie against and in the plane of the inner wall of the cap member, but the said clinching pockets of the cap member may be formed so that the clinched terminals of the prongs range inwardly and radially of the cap member to hold the parts together.

A further feature resides in a novel metal construction in seals for envelopes and the like, whereby the top or outside member of the device may take various ornamental shapes, or designs, such as a heart, a cross, an animal, a flower or flowers, etc.

A still further feature of the device is that the base member formed according to my invention may be used independently as a paper fastener if desired.

In the drawings:

Fig. 1 is a perspective and plan view of a pronged base plate comprising the male member of the seal,

Fig. 2 is a section and bottom view of a cap comprising the female member of the seal,

Fig. 3 is a back view of an open envelope showing the male parts of my seal in position to protect a letter,

Fig. 4 is a similar view with the closure flap of the envelope sealed.

Fig. 5 is a still similar view showing the female caps in place and the safety seals complete.

Fig. 6 is an enlarged section through one of the clinched safety seals.

Fig. 7 is a section and bottom view of a modified form of the female cap member.

Fig. 8 is an enlarged section through a clinched safety seal employing the modified cap shown in Fig. 7.

Referring to the figures, I show an ordinary envelope at 10, containing a letter 11, and 12 indicates my improved male base plate member, here shown in the form of a cross having arms 13 of equal lengths and formed with integral upstruck prongs 14 which are adapted to enter a mouth opening 15, leading into pockets 16 provided in a cap or female member 17, when the parts are forced together to lock the same in fixed relation.

The cap as shown here is semi-spherical but it may be shaped as desired.

The pockets 16 each have a curved top wall 18, the curve ranging laterally of the opening 15, or in a plane approximately parallel to the wall of the cap so that when the parts are pressed together the points of the prongs will be deflected to one side of said opening and over a cross or bridge plate 19 spanning the pockets 16, to interlock the parts as shown in Fig. 6, the planes of the bridge plates being radially arranged.

The cap 17 may be further formed with a serrated edge 20 which acts to readily tear the paper of the envelope should an unauthorized person attempt to tamper with the seal.

In the modified form of the female cap member 17^a, shown in Figs. 7 and 8 of the drawings, the pockets 16^a have the bridge plates 19^a arranged in a plane approximately parallel to the wall of the cap, so that when the parts are forced together, the prongs 14 will be clinched inwardly and radially, as in Fig. 8.

The construction shown in Fig. 6, wherein the points of the prongs are turned sideways, offers a stronger lock and is therefore preferred. In both cases the prongs 14 may be made of such lengths that their doubled up ends will reach backwards to the line of the lower edge of the female member, or even beyond the same in which case the respective pockets will be formed without a bottom, when the members are clinched together, or the said prongs may be left with shorter ends, as shown in the drawings.

The cap member and its pockets should be made of hard, light, strong, durable material, such as aluminum, steel, sheet brass, or similar hard substance, so that the prongs will not penetrate but will be clinched or de-

flected when they are urged or forced against the inner walls of said pockets, while the base member should be made of softer metal or material which has no spring quality but 5 is strong enough to effectively lock the cap in place when the prongs are clinched in the pockets.

The base plate may be formed with three, four, five, or six arms and an equal number 10 of prongs, or it may be made circular, square, triangular, hexagonal, or other shapes, if desired or required.

The cap member may be formed with a straight vertical side wall and a slightly 15 domed top to flatten the structure if desired.

When applying the base member to an envelope, the prongs may be forced through the letter and then through the sealed flaps 20 of the envelope, or the flaps may be forced through the flaps of the envelope only, as shown in Figs. 3 and 4 of the drawings.

The prongs are tapered so that the points

only will bend and the base portions being heavier will stand up under the clinching thrusts.

26

What I claim as new, is:—

A safety seal for an envelope, comprising a flat base member having radial arms, each being provided with an integral tapered prong to pass through said envelope, and a 30 semi-spherical cap member having pockets corresponding to the prongs of the base member, said pockets being provided with bridge plates over which the prongs are clinched when the parts are forced together 35 to provide an interlocking connection whereby the envelope is sealed, said cap member being also provided with serrated edges, along its plane circular edge to bite into the said envelope.

40

Signed at Elyria, in the county of Lorain, and State of Ohio, this 1st day of April, A. D. 1926.

LOUIS UNGER.
